MOTOR-CONTROLLING DEVICE.

1,032,826.

Specification of Letters Patent. Patented July 16, 1912.

Original application filed August 15, 1911, Serial No. 644,136. Divided and this application filed October 27, 1911. Serial No. 657,073.

To all whom it may concern:

Be it known that I, WALTER LOOMIS HAMILTON, a citizen of the United States of America, residing at Holyoke, in the county 5 of Hampden and State of Massachusetts, have invented a new and useful Motor-Controlling Device, the same being a divisional part of my application filed in the United States Patent Office August 15, 1911, Serial 10 No. 644,136, of which the following is a specification.

My invention relates to improvements in controlling means or mechanism for electrically-operated motors and the like, and 15 consists of a certain peculiar switch annulus and brush, together with opening means and engaging and releasing means for such annulus, all as hereinafter set forth.

The object of my invention is to produce 20 a reliable and highly efficient device for a motor or other electrically-driven or operated machine or apparatus, which device is easily operated and controlled and is especially well adapted for use with check-controlled or coin-operated apparatus for vending or dispensing machines, since it is capable of being made subject to such check-controlled apparatus and of combining therewith in a way to produce the best of 30 results.

A further object is to produce such a device which is comparatively inexpensive and simple in construction and operation, yet practicable and serviceable in the highest 35 degree.

Other objects will appear in the course of the following description.

As intimated above, this invention is particularly well adapted for use in connection 40 with vending machines which are equipped with or comprise motors and mechanism operated thereby, since it affords a readily controllable means by coin-operated apparatus or the like for making and breaking the circuit to the motor, and said invention is herein illustrated in its application to such a machine, although it is not to be understood that the invention is restricted to such application or thereby limited in its scope. 45 The machine just referred to is of the paper-towel-vending type.

A practical form of embodiment of the invention (as applied for towel-vending

purposes), whereby I attain the objects and 55 secure the advantages of the same, is illustrated in the accompanying drawings, and I will proceed to describe said invention with reference to said drawings, although it is to be understood that the form, construction, arrangement, etc., of the parts in various aspects are not material and may be modified 60 without departure from the spirit of the invention.

In the drawings, in which like numerals 65 designate like parts throughout the several views, Figure 1 is a front elevation of the lower half of a paper-towel-vending machine, in which my motor-controlling device is included, the door of the case being omitted and the switch casing being in section 70 so as to expose to view the interior of said case and casing with their contents; Fig. 2, a top plan of the parts and members shown in the preceding view, the door being here present and with the aforesaid case and casing being in section; Fig. 3, a section taken on lines 3—3, looking in the direction of the associated arrow, in Fig. 1, the elements of the motor-controlling device being in elevation; Fig. 4, a view similar to the preceding 75 except that the motor-controlling device is here shown in condition or readiness to start the motor after being released; Fig. 5, a detail of the latch for the movable section of the switch and of part of the operating arm 80 for such latch, the arm being in partial section; Fig. 6, a transverse vertical section taken on lines 6—6, looking in the direction 85 of the associated arrow, in Fig. 4; Fig. 7, an elevation of the motor-controlling device, 90 in which the eccentric is represented in position to elevate said movable section of the switch; Fig. 8, still another elevation of the same parts and members wherein said movable section is in its elevated position and the brush is about to slip into the gap formed 95 when said section was elevated, and, Fig. 9, a top plan showing abutting portions of the switch frame and segment, and the manner in which they come together and interlock. 100

Other arrows, besides those mentioned above, indicate the directions of moving parts.

Only brief mention will be made of the parts of the vending machine herein shown 105 and which do not constitute essential ele-

ments of the subject matter of this application. For fuller details in regard to the aforesaid parts, reference may be had to the application of which this application is a division, and to another divisional application filed on even date herewith.

The housing of the machine and for the motor-controlling device comprises a case 1 provided with a floor 2, a door 4, and a

10 casing 5 within said case 1 on said floor. The casing 5 is adjacent to the left-hand end of the case 1, and at the right-hand end of said case appears the lower portion of a coin chute 7 which is provided with a coin-guid-

15 ing member or tail-piece 8 and with a U-shaped coin-lever guide 9. The chute 7 opens above a pair of coin-guiding ears 10 which assist in directing the coin through a slot in the floor 2 into a money box 11, such slot being represented by dotted lines at 12 in Fig. 1. The box 11 is supported below the floor 2 by a pair of lugs 13 on a pair of ledges 14 extending inwardly from the ends of the case 1.

20 25 A strip of toweling is represented at 15, in Figs. 1 and 3, and this is fed down from a suitable supply and cut by and between a pair of feed-rollers 16 and a pair of cutting-rollers 17 and 18, the cutting roller 17 being provided with a blade or cutter 19 and the cutting-roller 18 having a slot 20 therein to accommodate said cutter when said cutting-rollers revolve. After being cut off the severed part of the strip or the towel passes

30 35 out of the machine at the bottom, suitable means of egress being provided to enable the strip to descend through the floor, behind the money box, and through the bottom of the housing.

40 45 An electric motor, represented at 21, is supported on the floor 2 adjacent to the right-hand end of the case 1, and this motor is controlled by the new device, and when energized drives the feed-rollers 16 and the cutting-rollers 17 and 18, through the medium of certain gears and pinions presently to be referred to more specifically.

The front feed-roller 16 is mounted fast on a shaft 22 that is journaled at opposite ends in suitable bearings which project inwardly from the ends of the case 1. The rear feed-roller 16 is mounted fast on a shaft 23 that is journaled at the left-hand end in a bearing which projects inwardly from the corresponding end of the case 1, and at the right-hand end in a bracket 24 which projects inwardly from the back side of said case. The cutting-rollers 17 and 18 are respectively mounted fast on shafts 25 and 26 that are journaled in the same way as the shaft 23. The motor 21 has a shaft 27 with a pinion 28 thereon. The pinion 28 meshes with a gear 29 which is rigidly connected with a pinion 30. The gear 29 and the pinion 30 are loosely mounted on a stud

31 which projects inwardly from the adjacent end of the case 1. The pinion 30 meshes with a large gear 32 fast on the shaft 22. Also fast on the shaft 22 is a gear 33 that meshes with a gear 34 on the shaft 23. 70

Rising from the floor 2, within the casing 5, is an inverted L-shaped bracket 35, and a shaft 36 is journaled in the upright part of said bracket and in the adjacent end of the case 1 after passing through the intervening side of said casing. Mounted fast on the shaft 36, between the casing 5 and the adjacent end of the case 1, is a large gear 37 which is driven by a meshing pinion 38 fast on the adjacent terminal of the shaft 22, and a large segmental gear 39 which imparts but one revolution to the cutting-rollers 17 and 18 while the feed-rollers 16 are making some half-dozen revolutions, more or less. 80

85 The segmental gear 39 drives the cutting-roller 17 directly by means of a pinion 40 fast on the shaft 25, with which said gear meshes, and the cutting-roller 18 receives its motion through the medium of a gear 41 fast on said shaft and a meshing gear 42 on the shaft 26. A brush arm 43 and an eccentric 44, which are members of the motor-controlling device and which will be more fully described hereinafter, are mounted fast on the shaft 36 within the casing 5, the eccentric being to the right of the brush arm. 90

95 The arm of the bracket 35 extends to the left from the upright part of the bracket, 100 and a trip-arm 45 is pivotally mounted, between the left-hand end of said bracket arm and a bearing 46 which extends inwardly from the adjacent side of the casing 5, on a pin 47 which passes through said bracket 105 arm, said trip-arm and said bearing. The trip-arm 45 passes out through a slot 48 in the front side of the casing 5, and the front terminal of said arm is bent downwardly and then forwardly to have attached thereto the lower end of a coiled spring 49. The upper end of the spring 49 is adjustably fastened by nuts 50 to an inwardly-extending lug 51 on the adjacent end of the case 1. A coin lever 52 is pivotally mounted at 53, a short distance from its left-hand end, on the trip-arm 45 outside of the casing 5, and the aforesaid end of the lever is fulcrumed beneath and against a bearing edge on the underside at the inner end of a lug 54. The lever 52 and the trip-arm 45 are arranged at right-angles to each other, and the former extends across the case, from left to right, to present a coin receiver 55, with which its free terminal is provided, beneath the chute 7, such free terminal and coin receiver operating within the guide 9 at the left of the tail-piece 8. The lug 54 projects inwardly from the left-hand end of the case 1. 110

115 120 125 130 The front feed-roller 16 is mounted fast on a shaft 22 that is journaled at opposite ends in suitable bearings which project inwardly from the ends of the case 1. The rear feed-roller 16 is mounted fast on a shaft 23 that is journaled at the left-hand end in a bearing which projects inwardly from the corresponding end of the case 1, and at the right-hand end in a bracket 24 which projects inwardly from the back side of said case. The cutting-rollers 17 and 18 are respectively mounted fast on shafts 25 and 26 that are journaled in the same way as the shaft 23. The motor 21 has a shaft 27 with a pinion 28 thereon. The pinion 28 meshes with a gear 29 which is rigidly connected with a pinion 30. The gear 29 and the pinion 30 are loosely mounted on a stud

The elements thus far pointed out, with the two exceptions noted and certain elements of the coin-operated appliance that have been explained, together with others 5 of said appliance yet to be explained, which coin-operated appliance elements constitute one operative means merely for the switch and may be changed to meet various conditions or to render the motor controlling device 10 applicable for other purposes besides the purpose for which the same is herein used, are incidental only to the embodiment of the present invention as herein set forth to illustrate how it may be practically applied, and such first-mentioned elements, like 15 said coin-operated appliance elements, will differ materially in different machines, even their omission altogether not affecting the invention in scope or otherwise.

20 I will now describe the motor-controlling device itself. Such device comprises a switch in the form of an annulus having a movable segment, holding and releasing means for said segment, elevating means 25 for said segment, and a brush for said switch, together with an electrical circuit to and through said switch to the motor 21. The switch consists of a frame 56 which is secured to the floor 2 within the casing 5, 30 and a movable section or segment 57 which is pivoted at the lower front end to the front end of said frame, at 58, and has a tooth or hook 59 on top, together with two pairs of contact pieces 60 fitted within said frame 35 and segment, one pair in each, and separated from the frame and segment by segmental insulators 61, one such insulator being interposed between the frame and the pair of contact pieces therein, and the other 40 such insulator being interposed between the segment and the pair of contact pieces provided for the same, and a segmental insulator 62 which separates the pair of contact pieces in the frame and another which separates 45 the pair in the segment. When the segment 57 with its contact pieces 60 and insulators 61 and 62 is closed, not only does the frame 56 with its segment form a complete ring or annulus, but the two insulators 61, the two pairs of contact pieces, and 50 the two insulators 62 do the same thing. The contact pieces 60 on each side of the insulators 62 are connected by a wire or jumper 63 so as to insure a continuity of circuit at 55 the joint adjacent to the pivot 58, whether the segment 57 be open or closed. A bow spring 64 is attached to the base of the frame 56 below the pivot 58, and extends upwardly to bear against the front of the segment 57 60 above said pivot and force said segment toward the back end of said frame or retain it in locking engagement with a latch 65 which is mounted over the switch on the pivot 47 and provided with a tooth or hook 66 arranged and adapted to engage and re-

lease the segment hook 59. The contiguous faces of the hooks 59 and 66 are so arranged, however, that very little power is required to overcome the force of the spring 64 and unlock the parts when the latch 65 is tilted 70 upward.

The holding and releasing means for the segment 57, in the present case, consists of the lever 52, the trip-arm 45, and the latch 65. In this connection it will be observed 75 that the part of the trip-arm 45 which is mounted directly on the pivot 47 is slotted at 67 to accommodate the latch 65 which is mounted on said pivot with said trip-arm. The hook 66 is on the bottom of the latch 65 behind the pivot 47, and there is a stop projection 68 at the front terminal of said latch, which projection is in front of said pivot. The under part of the trip-arm 45, which is adjacent to the projection 68, is 80 cut away to receive the latter, as clearly shown in Fig. 5. The latch 65 projects behind the hook 66, and being thus counterweighted normally rests with the stop projection 68 up against the trip-arm 45. The 85 trip-arm projects rearwardly over the latch and is counterweighted at 69 for the reason presently given. There is enough clearance between the latch and the overhanging terminal of the trip-arm to enable said latch to 90 function properly. When closed the segment 57 bears with its upper rear end on the corresponding end of the frame 56, closing the gap between such ends, as previously 95 intimated, and when opened said segment is 100 swung upwardly, and its hook 59 encounters the hook 66 and rocks the latch 65 upwardly out of the way until said hook 59 passes said hook 66, when said latch rocks down into normal position again with its hook now 105 behind the hook 59. The segment 57 is in this manner held up by the latch until the trip-arm 45 is carried down, against the resiliency of the spring 49, with the lever 52, as when a coin is dropped into the receiver 55, said trip-arm then rocking on the pivot 47 and actuating said latch, through the medium of the stop projection 68, and raising the hook 66 so that said hook becomes disengaged from the hook 59. Thus 110 the segment 57 is released to the influence of the spring 64 and permitted to drop and close the gap in the switch. The lever 52 swings downward, under the weight of the coin, on the point of fulcrum afforded by 115 the lug 54. The lever 52 is light, the spring 46 is properly adjusted, and said lever and the trip-arm 45 with the latch 65 are nicely balanced, to the end that the weight of a coin falling into the receiver 55 is sufficient 120 to overcome the force of the spring and of frictional and other resistance, upset the balance, and bring about the release of the segment 57. When the lever 52 is released by the coin or relieved from the weight 125

thereof, the spring 49 asserts itself and elevates the trip-arm 45 and with said trip-arm said lever. The force of the spring 49 becomes weaker as the trip-arm and the lever approach the ends of their upward travel, said spring having expended much of its energy before such ends are reached, but the combined weight of the latch and trip-arm behind the pivot 53, which has been of some assistance to the spring from the start, now furnishes enough added power owing to the new positions which the parts have already assumed, to bring about the complete restoration to normal positions and conditions of the parts being considered.

The segment 57 is actuated upward into engaging relation with the latch 65 by means of the eccentric 44 on the shaft 36, and a lug 70 which projects to the right, from the top of said segment, over said eccentric. In Fig. 3 the segment 57 is represented as being held up by the latch 65, and such segment is thus held in the general views. In Fig. 4 the parts have been actuated to release the segment which is in its low or closed position, and in Fig. 7 the eccentric 44 is in the act of raising said segment into locking engagement with the latch, the operation having been completed in the next view. As clearly shown, the eccentric raises the segment when the high part of said eccentric passes under the lug 70, the members being so proportioned and positioned that the eccentric encounters said lug at the time it is required that the segment be swung upwardly on the pivot 47.

The shaft 36 extends through the axial center of the switch annulus, and the arm 43 is mounted on said shaft within said annulus. A bifurcated brush 71, of spring metal, is attached to the outer end of the arm 43. The brush 71 is designed to contact forcibly with the contact pieces 60 and to travel around practically the entire course of their inner faces, one branch of said brush traveling around the two contact pieces on one side of the insulators 62 and the other branch of said brush traveling around the two contact pieces on the other side of said insulators. The space between the branches of the brush 71 enables said brush to clear the insulators 62. Inasmuch as the brush is insulated, when the same is in contact with the contact pieces 60, which are themselves insulated, the dead space is bridged and the circuit formed from the contact pieces on the side with which said brush is in engagement to the contact pieces on the other side with which said brush is in engagement, and the jumpers 63 connect electrically the two contact pieces on the two sides.

Referring again to Fig. 3, it will be observed that the brush 71 is in the space between the upraised end of the segment 57 and the adjacent end of the frame 56, con-

sequently out of contact with the contact pieces 60. Here, then, as in the general views, the circuit is broken at the switch. Passing to the next view, it will be seen that the segment 57 is down on the brush 71, hence the circuit at the switch is closed, and it remains closed while said brush makes one complete revolution or until said brush rides clear of the frame contact pieces into the space left by the segment when swung upwardly by the eccentric 44. In Figs. 7 and 8 the brush is shown at two different points in its revolution.

The motor 21 is in an electric circuit made up of a wire 72 which connects said motor with a suitable source of electrical energy outside of the case 1 and enters said case, with a wire 73, through the right-hand end thereof, a wire 74 which connects one of the jumpers 63 with said motor, and said wire 73 which connects the other jumper 63 with said source of electrical energy, together with said jumpers, the contact pieces 60 and the brush 71.

Provision for an interlocking joint between the free ends of the switch frame 56 and segment 67 may be made by forming a central tongue 75 at the upper rear end of said frame and by recessing the adjacent end of said segment to receive said tongue 95 when the segment comes down onto the frame. These tongued and grooved parts include portions of the contact pieces 60, hence any failure on the part of the segment, when it swings down, to form a good electrical contact with the frame is guarded against.

The operation of the motor-controlling device as a whole and the general operation of so much of the vending machine as is herein represented are as follows: A coin is dropped through the chute 7 into the receiver 55. The lever 52 is swung downward by the coin in the receiver 55, into the position indicated by dot-and-dash lines in Fig. 1, when said coin rolls out into the space between the ears 10 and from there through the slot 12 into the box 11. When depressed the lever 52 actuates the trip-arm 45 and causes the latch 65 to release the segment 57. The latter instantly snaps into its closed position, under the influence of the spring 64, and brings the upper pair of contact pieces 60 down onto the brush 71. This closes the circuit and the motor 21 is started. Meanwhile, the lever 52 rises with the trip-arm 45, under the influence of the spring 49 and the counterweights or counterweighted parts, into the former position, in readiness for the next coin, and at the same time the latch 65 is swung down to locate the hook 66 again in the path of the hook 59 when the segment 57 is subsequently elevated by the eccentric 44. Upon the closing of the circuit and the starting of the

motor, the feed-rollers are set in motion and continue to revolve until said motor stops, and while thus revolving said rollers feed down more and more of the toweling strip 5 15. By the time enough of the paper strip for a towel is fed down, said strip is severed by the following means and in the following manner: As the gear 37 approaches the end of its revolution, the segmental gear 39 engages the pinion 40 and thus causes the cutting-rollers to be set in motion, and before 10 said segmental gear leaves said pinion said rollers make a revolution and with the cutter sever the strip 15. While the strip-manipulating rollers are measuring off, as it were, and severing the towel, the brush 71 is making the circuit of the switch, and when said brush arrives at the upper end of the frame 15 56 and slips off of the same into the open space left by the segment 57 which is elevated just before this time into engaging 20 relation with the latch 65, by the eccentric 41, the electric circuit is opened and the motor stops with all of the members driven 25 thereby. It is understood, of course, that the brush arm 43 and the eccentric 44 receive their rotary motion from the motor, through the medium of the shaft 36, and the intervening gears, pinions and shafts, and that 30 they revolve once with the gear 37 at each cycle of the mechanism.

What I claim as my invention, and desire to secure by Letters Patent, is—

1. A switch annulus provided with means 35 to open and close a gap therein, and a rotary brush in operative relation to said annulus.

2. As a new article of manufacture, a switch in the form of an annulus having a movable section, such annulus including such 40 section being provided with insulated contact pieces which are insulated from each other.

3. As a new article of manufacture, a switch in the form of an annulus having a 45 movable section, such annulus including such section being provided with insulated contact pieces which are insulated from each other, and jumpers connecting said contact pieces on the two sides.

50 4. As a new article of manufacture, a switch frame and movable section arranged in the form of an annulus, such frame and section being provided with insulated contact pieces which are insulated from each 55 other, and yielding means to force the free end of said section toward the free end of said frame.

5. The combination, with a switch in the 60 form of an annulus having a movable section, such annulus including such section being provided with insulated contact pieces which are insulated from each other, of a

rotary brush arranged to bear on said contact pieces as it revolves.

6. The combination, with a switch in the 65 form of an annulus having a movable section, such annulus including such section being provided with insulated contact pieces which are insulated from each other, of a rotary brush arranged to bear as it revolves on 70 said contact pieces, means to move said section out of the path of said brush, and means to permit said section to move into such path.

7. The combination, with a switch in the 75 form of an annulus having a movable section, such annulus including such section being provided with insulated contact pieces which are insulated from each other, of a rotary brush arranged to bear on said contact pieces as it revolves, a latch for said 80 section, and an eccentric adapted to move said section out of the path of said brush into engagement with said latch.

8. The combination, with a switch in the 85 form of an annulus having a movable section, such annulus including such section being provided with insulated contact pieces which are insulated from each other, of a rotary brush arranged to bear on said contact pieces as it revolves, a latch for said 90 section, an eccentric adapted to move said section out of the path of said brush into engagement with said latch, and means to release said section from said latch and permit the former to move into said path. 95

9. The combination with a switch in the form of an annulus having a movable section, of a revoluble brush arranged in operative relation to said switch, and means to move said section to open a gap in such 100 annulus for said brush, and means to bring about the contact of said section with said brush while the latter is disposed in said gap.

10. The combination with a switch in the 105 form of an annulus having a pivotally attached segment, of a brush mounted to revolve within such annulus, an eccentric arranged to swing said segment out of the path of said brush, and means to hold said 110 segment after being actuated by said eccentric and subsequently to release it.

11. The combination with a switch in the 115 form of an annulus having a pivotally attached segment, of a brush mounted to revolve in such annulus, an eccentric arranged to swing said segment out of the path of said brush, and a locking and releasing latch for said segment.
